(57) **CLAIM**

We claim the ornamental design for a retractable, vehicular, center console display screen, as shown and described.

DESCRIPTION

FIG. 1 is a rear perspective view showing a retractable, vehicular, center console display screen of our new design, in a retracted position;

FIG. 2 is a rear plan view showing the retractable, vehicular, center console display screen of our new design, in the retracted position;

FIG. 3 is a top plan view showing the retractable, vehicular, center console display screen of our new design, in the retracted position;

FIG. 4 is a side plan view showing the retractable, vehicular, center console display screen of our new design, in the retracted position;

FIG. 5 is a side plan view, taken opposite that of FIG. 4, showing the retractable, vehicular, center console display screen of our new design, in the retracted position;

FIG. 6 is a rear perspective view showing the retractable, vehicular, center console display screen of our new design, in an extended position;

FIG. 7 is a rear plan view showing the retractable, vehicular, center console display screen of our new design, in the extended position;

FIG. 8 is a top plan view showing the retractable, vehicular, center console display screen of our new design, in the extended position;

FIG. 9 is a side plan view showing the retractable, vehicular, center console display screen of our new design, in the extended position; and,

FIG. 10 is a side plan view, taken opposite that of FIG. 9, showing the retractable, vehicular, center console display screen of our new design, in the extended position.

The broken lines (for example, a dashboard and a center floor-mounted console) are for illustrative purposes only and form no part of the claimed design.
